C. SCHÜTZ.
PORTABLE WATER HEATER,
APPLICATION FILED JAN. 16, 1913.

1,085,945.

Patented Feb. 3, 1914.

UNITED STATES PATENT OFFICE.

CONRAD SCHÜTZ, OF PHILADELPHIA, PENNSYLVANIA.

PORTABLE WATER-HEATER.

1,085,945.

Specification of Letters Patent.

Patented Feb. 3, 1914.

Application filed January 16, 1913. Serial No. 742,419.

To all whom it may concern:

Be it known that I, CONRAD SCHÜTZ, a citizen of the United States, residing at Philadelphia, in the county of Philadelphia and State of Pennsylvania, have invented 5 certain Improvements in Portable Water-Heaters, of which the following is a specification.

My invention relates to gas heaters and is 10 designed to obviate the escape of gas and danger resulting from the use of pilot tubes and similar contrivances in portable heaters by improving the ignition mechanism.

It is also an object to provide a simple, 15 efficient, convenient and durable construction.

Heretofore in devices of this character, it has been usual to use a torch or pilot tube to effect the ignition of gas supplied, independently of the ignition device, to the 20 burner within the casing. Explosions have been caused frequently by accumulation of gas in the heater due to prematurely turning on the supply to the burner or the failure 25 of the ignition device to work properly.

My invention contemplates the use of a single removable tube to supply gas to the burner and to effect ignition of the jets, gas flowing from the tube being lighted exteriorly 30 of the heater casing. The tube is adapted to be inserted in a socket communicating through a passage with the burner, and an orifice in such connecting passage or fuel 35 supply tube provides for the maintenance of a jet of burning gas after the seating of the tube in the socket, the balance of the unconsumed gas flowing to the burner, and the gas jets from the burner being ignited by the maintained flame.

40 Further characteristics of the construction embodying my invention will appear from the following description and the accompanying drawings in illustration thereof.

In the drawings, Figure 1 is a top plan 45 view of a heater embodying my invention; Fig. 2 is a transverse sectional view on the line 2—2 of Fig. 1; and Fig. 3 is a sectional view of details representing a modified construction.

50 The heater comprises a casing having the base 1, supported by the feet 2, and containing an air supply passage 3 communicating with the fresh air flue 4 extending above the level of the liquid in which the heater 55 is to be immersed and discharging through the circular passage 3'. A body 5 is fixed

on the base within the flanges 1' to form the combustion chamber 5', and contains a sight aperture 6 closed by a sheet of mica or other suitable material. Open ended tubes 7 for 60 the circulation of water pass through the walls of the body and have their ends upset against the exterior surface thereof so as to provide water tight joints. A chimney 65 extending to the height of the flue 4 is provided by the pipe 8 screwed into the aperture 9 in the top of the casing, and a passage for the insertion of the fuel supply tube is provided by the pipe 10 screwed into the casing opening 11 and extending to the 70 height of the part 8.

A burner 12, supported by the base 1, above and concentrically to the aperture 3', has a flange 12' on which is supported the spreading plate 13 containing jet openings 75 13'. A passage 14 extending through the burner's neck 15 contains a socket 16 and adjacent thereto lateral orifices 17. A gas supply tube 18, having an end 18' fitting the socket 16 and guiding rings 19 adapted to 80 loosely contact with the pipe 10, communicates with the Bunsen mixer 20, to which gas is supplied through a coupling 21 under control of the cock 22.

It will be understood that, when the apparatus is in operation, gas and air mixed 85 in the chamber 20 are supplied to the burner 12 through the conduit comprising the separable sections 18 and 15; that, in lighting the apparatus, the conduit section 18 is with- 90 drawn from the casing and the gas and air mixture supplied thereto ignited at the end thereof; and that, when the section 18 is seated in the socket 16, the jets issuing through the apertures 17 remain ignited 95 while the combustion of the main flow of fuel is smothered in the passage 14. The main flow of fuel then passes through the chamber 14' and holes 13' and is ignited 100 from the jets issuing from the apertures 17. 100

As shown in Fig. 3, the aperture 18" for the burner igniting jet is provided in the removable section 18 of the fuel supply conduit. The operation with this construction is substantially the same as with the construction of Fig. 2, the combustion of the main flow from the tube 18 being smothered in the passage 14 and the jets issuing from the burner orifices being ignited from the jet issuing from the aperture 18".

Having described my invention, I claim:

1. A portable heater comprising a casing,

a burner therein provided with jet orifices, and a conduit communicating with said burner and comprising separable sections joining in said casing, one of said sections having a jet aperture adjacent to an end thereof and to said orifices.

2. A portable heater comprising a casing having an air flue, a chimney and a pipe for passing a gas tube; a burner within said casing, a conduit communicating with said burner, and a second conduit in the form of a gas tube extending through said pipe

into frictional engagement and communication with said conduit first named, one of said conduits having in a side thereof a jet aperture adapted for igniting gas delivered by said connected conduits to said burner.

In testimony whereof I have hereunto set my hand this 15th day of January, 1913, in the presence of the subscribing witnesses. 20

CONRAD SCHÜTZ.
